UNITED STATES PATENT OFFICE.

OTTO G. HITCHCOCK, OF ERIE, PENNSYLVANIA, ASSIGNOR TO HAYS MANUFACTURING COMPANY, OF ERIE, PENNSYLVANIA, A CORPORATION OF PENNSYLVANIA.

VALVE.

No. 898,889.

Specification of Letters Patent. Patented Sept. 15, 1908.

Application filed April 23, 1908. Serial No. 428,854.

To all whom it may concern:

Be it known that I, OTTO G. HITCHCOCK, a citizen of the United States residing at Erie, in the county of Erie and state of Pennsylvania, have invented new and useful Improvements in Valves, of which the following is a specification.

This invention relates to valves and consists in certain improvements in the construction thereof as will be hereinafter fully described and pointed out in the claims.

More particularly the invention relates to a valve which is adapted to effect a closure at one side of the valve, and a waste from the opposite side of the valve to perform the functions that are ordinarily performed by waste cocks.

The invention is illustrated in the accompanying drawings as follows: Figure 1 shows a central vertical section of the valve. Fig. 2 a vertical section of the valve disk, and a portion of the stem.

1 marks the valve body on which there is the diaphragm 2. The valve opening 3 extends through this diaphragm, and the valve is opened by movement toward and from this diaphragm. The valve disk 4 operates on the seat surrounding the opening 3. It is secured to a stem 5 by means of a screw 5a. The stem has the screw thread preferably immediately above the disk 4. This operates on the screw thread 8 arranged in the extension valve chamber 7.

A closure is effected by a series of leather disks 9 resting on a metal disk 11. The metal disk rests on the shoulder 10 in the chamber 7. The leather disks are held in place and put under compression by the waste cap 12. This is provided with the annular shoulder 13 which is engaged by the flange nut 14, the flange nut being secured to the exterior of the chamber 7. A passage or chamber 15 is formed in the waste cap 12, and communicates with the waste or dirt nozzle 16. The upper end of the cap is closed by a gland 17 in which is packed the packing 18 put under compression by follower 19.

The stem has the opening 20 which extends upwardly from the bottom of the stem a sufficient

distance to reach through the closure formed by the washers 9 when the valve disk is on its seat. This passage is screw threaded at the bottom and is preferably closed immediately above the screw thread by the plug 21. A cross passage 22 is arranged through the stem at a point just below the metal washer 11 when the valve disk 4 is on its seat. A second cross passage is arranged through the stem immediately above the closure formed by the washers 9. The openings 22 and 23 lead from or enter the opening 20, so that a means of communication is established from below the closure in the valve chamber to above it when the valve is closed. An opening 24 extends through the screw threaded part of the stem, so that the valve chamber 7 is in communication with the waste or discharge side of the body at all times.

When the valve is closed the discharge side of the body can drain through the passage 24, chamber 7, cross passage 22, opening 20, cross passage 23, chamber 15 and nozzle 16. As soon as the valve disk is opened the cross passage 22 is brought into the closure thus preventing a back leakage from the discharge end of the body when the valve is opened.

With this invention the waste passage is closed almost immediately with the initial opening of the valve, so that little difficulty is experienced by leakage by reason of back pressure. It also forms a construction which can be cheaply manufactured. It will be noted that the waste cap 12 can be turned in any direction, the friction on the leather washer being sufficient to hold it in place, but not so great to prevent its ready turning.

What I claim as new is:

In a valve, the combination of a valve body having a screw threaded extension chamber 7 thereon, said chamber being provided with a packing chamber terminating in the shoulder 10; a metal disk resting on the shoulder 10, packing means resting on the metal disk and located within the chamber; a valve disk operating upon the valve seat; a stem secured to the disk, and having a screw thread thereon for operating in the screw thread extension, said stem having a passage

forming a means of communication through the packing when the valve is closed, said passage being closed by the packing when the valve is open; a follower entering the chamber and resting upon the packing and containing a drain passage; and a nut for exerting pressure upon the follower.

In testimony whereof I have hereunto set my hand in the presence of two subscribing witnesses.

OTTO G. HITCHCOCK.
